UNITED STATES PATENT OFFICE.

CHARLES SIMPSON YOUREE, OF LOS ANGELES, CALIFORNIA.

DESIGN FOR AN AUTOMOBILE LIGHT.

Application filed June 21, 1926. Serial No. 18,132. Term of patent 3½ years.

To all whom it may concern:

Be it known that I, CHARLES SIMPSON YOUREE, a citizen of the United States, residing in the city of Los Angeles, in the county of Los Angeles and State of California, have invented a new, original, and ornamental Design for Automobile Lights, of which the following is a specification, reference being had to the accompanying drawing, forming a part thereof, in which the figure is a perspective view of an automobile light embodying my design.

I claim:—

The ornamental design for an automobile light, as shown.

In testimony whereof, I affix my signature.

CHARLES SIMPSON YOUREE.
